COLUMN CLIMBER

Harold E. Erwin, 2117 Missouri St., Keokuk, Iowa
Filed Mar. 7, 1963, Ser. No. 263,625
10 Claims. (Cl. 182—134)

This invention relates to an improved climber of extremely simple construction adapted to be fastened to a shoe or boot and having portions adapted to straddle a flange of a structural member and to assume a binding engagement therewith when the user's weight is placed on the climber to enable the user to readily climb structural members such as metal I-beams, channels or the like.

Another object of the invention is to provide a climber which is so constructed that the center of gravity thereof is set inwardly with respect to an outer edge of the flange of the structural member engaged by the climber, so that said climber will not tend to rock outwardly relative to said outer edge of the flange and toward a disengaged position, even when the weight of the user is shifted outwardly and away from the structural member.

A further object of the invention is to provide a climber having novel means to prevent rocking of the climber relative to a flange which is engaged thereby.

Still another object of the invention is to provide a climber which may be readily adjusted to accommodate flanges of different thicknesses.

Various other objects and advantages of the invention will hereinafter become more fully apparent from the following description of the drawings, illustrating presently preferred embodiments thereof, and wherein:

FIGURE 1 is a side elevational view of a preferred form of the climber for use on the left shoe, and shown in an applied position;

FIGURE 2 is a top plan view thereof;

FIGURE 3 is an enlarged cross sectional view, partly in elevation, taken substantially along the line 3—3 of FIGURE 2;

FIGURE 4 is an enlarged cross sectional view taken substantially along the line 4—4 of FIGURE 2;

FIGURE 5 is a top plan view, partly broken away, illustrating the climber on the right shoe;

FIGURE 6 is an elevational view of one element of the climber;

FIGURE 7 is an enlarged detailed cross sectional view taken along a plane as indicated by the line 7—7 of FIGURE 2;

FIGURE 8 is a top plan view of one element of the climber;

FIGURE 9 is a similar view of another element thereof;

FIGURE 10 is an end elevational view of a slightly modified form of the climber, and

FIGURE 11 is an enlarged side elevational view thereof, partly in section and partly broken away.

Referring more specifically to the drawings and first with reference to FIGURES 1 to 4 and 6 to 9, the column climber in its entirety and comprising the invention is designated generally 12, and includes an elongated rigid bar 13 which is preferably formed of strap iron of sufficient thickness so that said bar can readily support the weight of a man without bending. One end of the bar 13 is beveled on its upper side, as seen at 14, to provide a sharp bottom edge 15. An arcuate notch 16, as best seen in FIGURE 9, is cut in the edge 15, intermediate of

2

its ends. The beveled surface 14, including the edge 15, is hardened or hard surfaced in any conventional manner. The bar 13 is provided adjacent its ends with longitudinally extending openings or slots 17 and 18, as seen in FIGURE 9. The outer end of the slot 17 terminates adjacent the beveled surface 14 while the outer end of the slot 18 terminates adjacent the other end of the bar 13. The slot 18 is preferably narrower and somewhat longer than the slot 17.

10 The climber 12 includes a spacing member, designated generally 19, which is formed from a sheet of metal the side edge portions of which are bent at right angles to form parallel flanges 20 and 20' which are spaced apart a distance to straddle the bar 13 which fits snugly therebetween. The piece from which the spacing member 19 is formed is cut out between the flanges 20 and 20', except at the ends thereof, to provide a bridge member 21 extending between the upper edges of the flanges at one end of the spacing member 19 and a bridge member 22 which extends between the upper edges of the flanges 20 and 20' at the other end of said spacing member 19. As seen in FIGURE 1, the bridge members 21 and 22 have their undersides disposed flush with the upper edges of the portions of the flanges 20 and 20' disposed between 25 said bridge members so that the bridge members are upwardly offset relative to said flanges. The widths of the flanges 20 and 20', between the bridge members 21 and 22, correspond with the thickness of the bar 13, so that when the bridge members are resting upon the upper surface of said bar the upper edges of the flanges 20 and 20', between the bridge members, are disposed flush with the upper surface of the bar 13 and the bottom edges of said flanges are disposed flush with the underside of said bar, as seen in FIGURE 1. The spacing member 19 is of a 30 length somewhat less than the distance between the remote ends of the slots 17 and 18 and substantially greater than the distance between the adjacent ends of said slots. The bridge member 21 has a circular opening 23 of a diameter equal to the width of the slot 17 and the bridge member 22 has an elongated slot 24 of a width corresponding to the width of the slot 18.

A column binder clamp, designated generally 25, comprises a yoke-shaped member of rigid construction, preferably formed from steel plate of substantial thickness as 45 shown and which includes spaced parallel legs 26 and 27 and an intermediate portion 28 which extends between and connects complementary ends of said legs. The leg 27 has a downturned terminal end 29, which is disposed beyond the terminal end of the leg 26, and said leg 27 has an opening 30 which is located nearer the downturned terminal 29 than the intermediate portion 28. The clamp 25 is bent approximately along a line 31, transversely through the intermediate portion 28, so that the two ends of said intermediate portion form an angle of approximately 150° and so that the plane of the leg 27 is disposed at an angle of approximately 150° to the plane of the leg 26, as seen in FIGURE 1. The portions 26, 27 and 28 form a large recess 32 of uniform width having an open end opening outwardly between the terminal or distal 55 ends of the legs 26 and 27.

60 A headed bolt 33 extends upwardly through the slot 17 and through the opening 23 of the bridge member 21. Said bolt passes upwardly through the opening 30 of the leg 27 for mounting said leg crosswise of the bar 13 and spacing member 19 and with its downturned terminal 29

abutting against the flange 20, as seen in FIGURE 4, to prevent the binder clamp 25 from turning relative to the bolt 33. When the clamp 25 is thus mounted, as seen in FIGURES 1 and 2, the outer part of the intermediate portion 28 and the leg 26 are inclined upwardly relative to the leg 27 and the part of the intermediate portion 28 which projects therefrom, and said leg 26 is spaced outwardly from the end of the bar 13 as defined by the sharpened edge 15.

A stationary sole clamp 34 is formed from a single strip of rigid metal having a flat apertured end 35 which rests upon the bridge member 21, which is disposed between said bridge member and a part of the leg 27, and through which the bolt 33 extends. The clamp 34 has an upwardly extending intermediate portion 36 which bears against the outer edge 37 of the leg 27, and a top portion 38 which extends from the upper end of the intermediate portion 36 in the opposite direction to the base portion 35 and which is disposed substantially parallel thereto. A nut 39 threadedly engages the upper portion of the bolt 33 and a split lock washer 40 is mounted on said bolt between the nut 39 and the leg 27 for securing all of the parts engaged by said bolt immovable relative to one another when the nut 39 is tightened.

As best seen in FIGURE 3, a headed bolt 41 extends upwardly through the slot 18 and slot 24. A releasable sole clamp, designated generally 42, includes a lever 43 having a disc shaped head 44 at one end thereof. A short shaft 45 is secured to the underside of the head 44 and is disposed eccentrically thereof. The head 44 has an opening 46 which aligns with a bore 47 of the shaft 45, which opening and bore are eccentrically disposed relative to the head and shaft. A bracing web 48 is secured to the underside of the lever 43 and against a portion of the periphery of the shaft 45. The lower end of the shaft 45 rests on the bridge 22 and the bolt 41 extends upwardly through a bushing 49 which extends through the opening 46 and bore 47 and which also rests upon the bridge 22 and is of a length to extend slightly above the upper surface of the head 44. A nut 50 threadedly engages the upper portion of the bolt 41 and a lock washer 51 is mounted on said bolt between said nut and the upper end of the bushing 49. Accordingly, when the nuts 39 and 50 are tightened, the spacing member and the other parts which engage the bolts 33 and 41, with the exception of the sole clamp 42, will be immovably mounted on the bar 13. The periphery of the shaft 45 includes a cutaway portion forming a flat surface 52 which is disposed remote from the axis of the bore 47. A part of the head 44 overlies the surface 52. An end 53 of the surface 52, which is disposed remote from the lever 43, is disposed more remote from the axis of the bore 47 than any other portion of the periphery of the shaft 45.

The climber 12 is shown in FIGURES 1, 2 and 3 clamped to the instep 54 of the sole of a left shoe 55. The inner end or edge of the bridge 21 and the sole clamp portion 36 abut the inner edge of the instep portion 54, while the sole clamp portion 38 overlies the upper surface of said inner edge of the sole portion 54. The inner end or edge of the bridge 22 and the flat surface 52 abut the outer edge of the instep portion 54, and a part of the disc 44 overlies the upper surface of said outer edge for securely clamping the climber 12 to the shoe sole with the flange 20' abutting the forward or inner end of the shoe heel 56, as seen in FIGURE 3, and with the upper surface of the bar 13 and the upper edges of the flanges 20 and 20', between the bridge members 21 and 22, bearing against the underside of the instep portion 54. In this position the lever 43 extends rearwardly along the outer side of the heel 56. To release the climber 12, said lever 43 is swung clockwise from its position of FIGURE 2 through an arc of approximately 180° to position the portion of the periphery of the shaft 45, located nearest the bore 47, between said bore and the outer edge of the sole 54. During this movement the peripheral portion 53

passes between the outer edge of the sole 54 and the bore 47 to effect an unlocking of the sole clamp 42. The lever 43 is swung counterclockwise through an arc of approximately 180° to its position of FIGURE 2 for locking the climber 12 on the shoe sole 54. As the portion 53 moves between the outer edge of the sole 54 and the bore 47 to effect locking of the clamp 42, it will tend to move the climber 12 rearwardly of the sole 54 and against the shoe heel 56.

The inner wall 57 of the outer clamp leg 26 is disposed substantially parallel to the beveled surface 14, above and outwardly thereof, and the upper edge 58 of said wall 57 forms the biting edge of the clamp 25 which cooperates with the biting edge 15. The distance that the edge 58 is spaced outwardly from the edge 15 can be varied by sliding the spacing member 19 and the parts supported thereon longitudinally of the bar 13, when the nuts 39 and 50 are loosened, to adjust the climber 12 to flanges 59 of different thicknesses.

Assuming that the climber 12 is secured to the left shoe 55 for climbing an upright structural member 60, such as an I-beam, a portion of which is shown in FIGURES 1 and 2 and of which the flange 59 constitutes the left hand flange, as viewed by the wearer of the climber 12 who is facing the structural member 60, it will be readily apparent that by turning the left shoe 55 inwardly so that the climber 12 will be inclined downwardly toward the clamp 25, that the flange 59 will be received in the notch 32 between the surfaces 14 and 57 when the climber is moved transversely toward said flange 59. The user by then placing his weight on his left foot will cause the climber 12 to rock counterclockwise to its position of FIGURE 1, so that the edge 15 will bite into the outer surface of the flange 59 while the edge 58 will bite into the inner surface thereof, to effectively bind the climber 12 to the flange 59 so that it cannot slip downwardly relative to the column 60 while the user's weight is supported at least partially thereon. To move the climber 12 upwardly or downwardly of the column 60, the weight of the user is transferred therefrom onto a climber attached to the other right foot, which will hereinafter be described, so that the left foot can be manipulated to rock the climber 12 clockwise as seen in FIGURE 1 sufficiently to release the edges 15 and 58 from biting engagement with the outer and inner sides, respectively, of the flange 59, and so that the climber 12 can then be moved vertically of the column 60, and the operation, previously described, repeated for reclamping the climber to the flange.

It will be noted that the closed end of the recess 32 which abuts the outer edge 61 of the flange 59 is spaced outwardly a substantial distance laterally from the bar 13, so that the bar 13, which is disposed perpendicular to the flange 59, is offset inwardly a substantial distance from the outer edge 61 of the flange toward the plane of the web 62 of the column 60. Consequently, the center of gravity of the climber 12 is offset from the outer edge 61 of the flange inwardly toward the plane of the web 62, to minimize any tendency that the climber 12 might have to rock away from the column 60 and toward a released position, and so that the user will not have to exert a downward pressure with the forward part of his foot to retain the climber in correct binding engagement with the flange 59. The notch 16 is provided to divide the edge 15 into two spaced portions. Said two halves of the edge 15 provide, in effect, two separate biting edges which hold the bar 13 against slippage relative to the flange 59 when the user's weight shifts as he climbs the column 60, due to the two edges 15 biting into the outer surface of the flange 59 and preventing the bar 13 from twisting relative to the flange about its longitudinal axis.

The nut 50 can be loosened so that the parts carried by the bolt 41, including the sole clamp 42, may be adjusted longitudinally of the spacing member 19 and bar 13 by sliding the bolt 41 in the slots 18 and 24 of said bar 13

and the bridge member 22, respectively, for accommodating the climber 12 to instep portions 54 of different widths.

It will also be apparent from FIGURE 3 that the climber 12 when applied to the shoe 55 is upwardly offset relative to the plane of the shoe sole and heel so that the user may walk without inconvenience with the climber attached to his shoe.

FIGURE 5 illustrates a climber, designated generally 63, for use on the right foot and which is identical to the climber 12 except that the column binder clamp 25a is reversed relative to the clamp 25 so that the recess 32a thereof opens in the opposite direction to the recess 32; and the releasable sole clamp 42a which is likewise reversed relative to the clamp 42. The clamp 42a, as seen in FIGURE 5, swings forwardly in a counterclockwise direction to a released position to move the surface 52a of the shaft 45a to a position outwardly rather than inwardly of the bolt 41a. The bar 13a, spacing member 19a and the other parts of the climber 63 are identical with corresponding parts of the climber 12. However, in the climber 63 the closed end of the notch 32a is offset laterally away from the flange 20a, which corresponds to the flange 20 of the climber 12. The climber 63 engages the other right hand flange 59a of the column 60.

FIGURES 10 and 11 illustrate a slightly modified form of the climber, designated generally 64, and which is adapted to be worn on rubber insulated boots, wedge-type soles, and other types of footwear which do not have a conventional, substantially rigid sole to accommodate the sole engaging clamps 34 and 42. Accordingly, the clamp 42 including the bushing 49 and the sole clamp 34 are dispensed with and are replaced by two corresponding metal strap anchoring members 65 and 66 each including an apertured base 67 and an upwardly extending strap portion 68 having a transversely elongated slot or opening 69 near its upper end. The base 67 of the member 65 assumes the position normally occupied by the base 35, between the leg 27 and the bridge member 21, with the bolt 33 extending upwardly therethrough. The part 68 extends upwardly along the inner edge 37 and is flared outwardly thereabove, as seen in FIGURE 11. The base 67 of the other anchor member 66 is disposed between the bridge 22 and the lock washer 51 with a bolt 41a extending upwardly therethrough. The bolt 41a is shorter than the bolt 41. The portion 68 of the member 66 extends upwardly on the inner side of the bolt 41a and is flared outwardly thereabove.

One end of a flexible strap 70 is looped through the opening 69 of the anchor member 66 and an end of a flexible strap 71 is looped through the opening 69 of the anchor member 65. One end of a strap 72 is disposed in the loop of the strap 70 and is anchored to both halves of said loop by a fastening 73, and a similar fastening 73 connects the other end of the strap 72 to both halves of the loop of the strap 71. The strap 70 has a buckle 74 on its other end for securing the straps 70 and 71 together over the instep 75 of a shoe or boot 76 and with the strap 72 extending around the shoe counter for holding the bar 13 and spacing member 19 against the underside of the instep portion 77 of the shoe sole and against the shoe heel 78, as clearly illustrated in FIGURE 10.

The climber 64 is otherwise identical with the climber 12, and a further description of its construction and use in connection with the column flange 59 is considered unnecessary.

Various other modifications and changes are contemplated and may be resorted to, without departing from the function or scope of the invention as hereinafter defined by the appended claims.

I claim as my invention:

1. A climbing device for climbing flanged structural members comprising an elongated rigid bar having a beveled inner end defining a biting edge, an elongated spacing member mounted on said bar, a first fastening

means and a second fastening means detachably securing the spacing member to the bar, footwear engaging means attached to the first and second fastening means and adapted to secure the climber to an item of footwear with the bar and spacing member disposed under the footwear sole and crosswise thereof and with said inner bar end protruding from an inner side of the footwear, said first fastening means being disposed adjacent said inner bar end, a column binder comprising an inner leg, an outer leg and an intermediate portion connecting corresponding ends of said legs and combining therewith to define a recess between said legs closed at one end by said intermediate portion and having an opposite open end, said inner leg being engaged by said first fastening means for securing the column binder immovably to said bar and spacing member, said outer leg having an inner biting edge disposed parallel to said biting edge of the bar and spaced outwardly and upwardly therefrom and adapted to engage an inner surface of a flange of a structural member the outer surface of which is engaged by the biting edge of the bar when the flange is received in said recess between said inner bar end and said outer leg.

2. A climbing device as in claim 1, said outer leg and at least a part of said intermediate portion of the binder clamp being inclined downwardly and inwardly toward said inner leg, said biting edge of the outer leg being formed by an inner wall and top surface of said outer leg.

3. A climbing device as in claim 1, said first and second fastening means, the spacing member and the parts carried by said fastening means being longitudinally adjustable relative to said bar for varying the spacing between the biting edge of the bar and the biting edge of said outer leg for accommodating flanges of different thicknesses.

4. A climbing device as in claim 1, said biting edge of the bar being composed of longitudinally spaced end portions for minimizing rocking or twisting of the bar relative to a flange engaged by the biting edges.

5. A climbing device as in claim 1, said intermediate portion of the column binder clamp being laterally offset outwardly from an adjacent side edge of said bar and being adapted to abut an outer edge of the flange for positioning the center of gravity of the climber inwardly with respect to the outer edge of the flange.

6. A climbing device as in claim 1, said second fastening means being longitudinally adjustable relative to the first fastening means, the bar and spacing member for varying the spacing between the parts of the footwear engaging means connected to the first fastening means and second fastening means for accommodating footwear items of different widths.

7. A climbing device as in claim 1, said footwear engaging means including a stationary rigid clamp connected to said first fastening means and having a part upwardly offset from the bar and spacing member and adapted to overlie an inner edge portion of the footwear sole, and a clamp rotatively connected to said second fastening means including a flange portion adapted to overlie a part of the upper surface of the outer edge of the sole and an eccentric portion adapted to engage against said outer edge and movable toward and away from the stationary sole clamp by rotation thereof for releasably clamping the footwear sole between said sole clamps.

8. A climbing device as in claim 7, said eccentric portion including a substantially flat surface disposed remote from the axis of rotation thereof and adapted to abut the footwear sole in a clamping position thereof, and said flat surface having an end disposed remote from the axis of rotation of said eccentric portion and movable between said axis of rotation and the shoe sole during rotation of the rotatable clamp between a locked position and an unlocked position thereof.

9. A climbing device as in claim 1, said footwear engaging means comprising anchor members connected to said first fastening means and the second fastening means and

straps secured to said anchoring members and forming a detachable harness adapted to engage over an instep portion and around a counter of the footwear.

10. A climbing device as in claim 1, said spacing member including transversely spaced substantially parallel flanges straddling said bar and bridge members extending between the upper edges of the end portions of said flanges, said bridge members engaging the upper surface

of the bar and said fastening means extending through said bridge members.
